FOUNTAIN MOP AND WASHER HEAD

Original Filed Dec. 4, 1925

Inventor:
Leon Hemple.
By *Fred J. Hanson*
Attorney.

UNITED STATES PATENT OFFICE

LEON HEMPLE, OF ST. LOUIS, MISSOURI

FOUNTAIN MOP AND WASHER HEAD

Application filed December 4, 1925, Serial No. 73,103. Renewed March 7, 1929.

My invention relates to fountain mops and washer heads, and, has for its object the provision of a device which is a distinct and practical improvement to overcome certain practical objections to, and defects in the character of device, as set out in my co-pending application, Serial Number 654,595.

A further object of the invention is the provision of a mop and washer head structure which will effectively retard the velocity of the flow of water before flowing into and through the absorbent mop and washer head material so as to saturate the cords with water rather than cause the flow to pass rapidly through the cords which causes the water to splash, especially when holding the device in the hand, as when washing a vehicle body and the like.

A further object of the invention is to provide a hollow core for the mop and washer head so constructed as to retard the velocity of the flow of water at the inner extremity of the core and to cause it to flow laterally from the core upon opposite sides thereof at the inner end thereof, thereby avoiding the splashing of water while using the device.

A still further object of the invention resides in the manner in which I tie the mop or washer cords to the core; first, by folding the cords and tying them below the inner end of the core so as to provide a cover for the inner end of the core; second, by tying the cords adjacent the upper side of the lateral core projection near the outer end of the core so as to draw the cords tightly and closely around the water discharge passages at the inner end of the core so as to prevent slipping of the cords and further retard the flow of water from the core; and third, to further and finally tie the cords adjacent the lower sides of the lateral core projections to prevent any possible displacement of the cords upon the core of the device.

With the above and other objects in view, the invention consists in the novel features of construction, arrangement and combination of parts and their equivalents, hereinafter more fully described and finally pointed out in the claims hereto appended.

Referring to the accompanying drawings

forming a part of this specification, wherein like characters of reference denote similar parts throughout the several views:

Fig. 1, is a side elevation of my improved mop and washer head.

55

Fig. 2, is a side elevation of the mop and washer head core.

Fig. 3, is a top plan view thereof.

Fig. 4, is a view, substantially full size, in vertical sectional elevation, embodying the features of my invention.

Fig. 5, is a detail of a modification of the inner end of the core.

Referring to the drawings, the reference character 1 represents a suitable hose, pipe, hollow handle or the like having its lower end provided with an externally screw threaded nipple 2.

In carrying out the aim of my particular invention, I employ a core or nozzle 3 having the water chamber or passage 4. The upper end of the chamber or passage 4 is internally screw threaded so as to provide the screw threaded socket 5 for receiving the nipple 2 when connecting the hose 1, or the like to the nozzle or hollow core, as shown in Fig. 4.

The upper end of the chamber or passage 4 at the base of the internally screw threaded socket 5 is provided with an annular shoulder 6 upon which can be seated a suitable washer 7. The inner walls 8 of the core nozzle 3 are preferably parallel so as not to increase the velocity of the water flow therethrough.

The lower end of the core nozzle 3 is preferably closed by means of the inner end wall 9 which is connected to the inner end of the core nozzle 3 in spaced relation to the lower edge 10 thereof, by means of a pair of opposed integral connections or arms 11, so as to provide or form two opposed laterally directed water discharge passages 12 at the inner end of the core nozzle, as shown in Figs. 2 and 4. In other words, the wall of the core nozzle 3 is cut away upon opposite sides just above the inner end wall 9 thereof to provide suitable water discharge passages at the inner end of the nozzle.

The wall of the core nozzle 3 is preferably greater in diameter at its outer end than at its main body portion to provide the nipple

100

receiving socket 5 and to provide a circumferential shoulder 13.

Projecting laterally in opposite directions from the wall of the main body portion of the core nozzle 3, are a pair of suitable preferably integral arms 14, which are disposed a suitable distance inward from the circumferential shoulder 13 which arms act as anchors and aid in preventing the displacement of the fabric cords as will be hereinafter set out.

The reference character 15 represents the mop and washer head body and it is formed of the usual fabric cords positioned around the core nozzle 3 thereof in such a manner as to 10 extend beyond the inner end 10 of the core nozzle 3 to provide the mopping and washing body 15 at the free ends and a compact outer head 16 around the core nozzle, as well as a compact inner head 17 below the inner end 15 wall 10 of the core nozzle, as clearly shown in Fig. 4. The fabric cords forming the inner head 17 are tied by suitable means, such as a cord 18 just below the inner end wall 10 of the core nozzle 3. The fabric mop and washer head cords are then tightly drawn and directed toward the socket end of the nozzle engaging the outer surface of the nozzle wall so as to span and close the water discharge openings in passages 12 and they pass upon 20 either side of the laterally projecting arms 14. This section of the cords form a mass, body or inner wall of cords designated 19 which are tightly massed so as to materially restrict and retard the flow of water between 25 the cords so as to cause the cords to merely absorb the water rather than permit the water to flow rapidly therebetween and therethrough. This mass of cords designated section 19 are tied by suitable means, such as 30 a cord 20 above the arms 14 adjacent the circumferential shoulder 13 to prevent longitudinal movement of the cords with relation to the core nozzle 3. The mop and washer head cords are then folded upon themselves 35 and directed downwardly or toward the inner end of the core nozzle and are again and finally tied a third time as at 20' below the lateral extending arms 14 adjacent the outer ends thereof to form or provide the massed 40 outer cord head 16 and to positively prevent displacement of the mop and washer head cords around the core nozzle 3, as will be apparent from Fig. 4, of the drawing. The remaining or free ends of the cords which 45 constitute the mop or washer head body 15 extend below the inner cord head 17 and completely surround the same, as clearly shown in Fig. 4.

It will be apparent from the foregoing description and by reference to the drawings, that the flow of water into the chamber or passage 4 of the core nozzle 3 is abruptly stopped by the inner end wall 10 only after the velocity of the flow has been disturbed or retarded and permitted to flow or be dis-

charged laterally from the inner end of the core nozzle 3 by being absorbed by the mop and washer head cords, instead of being permitted to flow through the mop cords without being first materially retarded in its velocity. By the arrangement herein set out with reference to the cord assemblage about the core nozzle, water from the nozzle will not splash nor come through the cords with such force as to disturb the user thereof, as the water only flows gently through the cords and by absorption, owing to the tightly drawn and packed cord wall 19 blocking the free passage of water being discharged from the core nozzle 3.

In the modification shown in Fig. 4, it will be observed that in some instances, it may be advisable to permit of a more free flow of water from the core nozzle and in this case, I provide the end wall 10 with one or more suitable water discharge openings 21 so as to permit some of the water to pass straight through the core nozzle and into the inner core head 18 without being first diverted or materially retarded.

From the foregoing description, it is evident that I provide a fountain mop and washer head wherein the flow of water therethrough is so retarded as to obviate splashing of water at the mop or washer head.

The many advantages of the herein described invention will readily suggest themselves to those skilled in the art to which it appertains.

I do not desire to be understood as limiting myself to the exact details of construction and arrangement of parts as herein described and illustrated, as it is manifest that variations and modifications may be made without departing from the spirit and scope of my invention and the terms of the following claims, hence I wish it to be understood that I reserve the right to make any such changes, or modifications as may fairly fall within the scope of the appended claims when fairly construed.

What I claim is:

1. In combination, a core nozzle for attachment to a hose, mop cords applied to said nozzle, said cords being folded intermediate their ends to provide an inner ply of strands and an outer ply of strands, anchor pins directed laterally from the nozzle and embedded in both the inner and outer strands, means securing the inner ply of strands to the nozzle above the anchor pins, means securing the outer ply of strands to the inner ply of strands below the anchor pins, means tying the inner ply of strands together below the nozzle and said nozzle having laterally directed water outlet openings in its wall leading from the bore thereof into the inner ply of strands.

2. In combination, a core nozzle for attachment to a hose, mop cords applied to said nozzle, said cords being folded intermediate

their ends to provide an inner ply of strands and an outer ply of strands, anchor pins directed laterally from the nozzle and embedded in the inner strands, means securing the inner ply of strands to the nozzle above the anchor pins, means securing the outer ply of strands to the inner ply of strands below the anchor pins, means tying the inner ply of strands together below the nozzle and said nozzle having laterally directed water outlet openings in its wall leading from the bore thereof into the inner ply of strands.

In testimony whereof, I have hereunto signed my name to the specification.

LEON HEMPLE.
